UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-HANDLE.

SPECIFICATION forming part of Design No. 21,775, dated August 9, 1892.

Application filed July 11, 1892. Serial No. 439,707. Term of patent 7 years.

To all whom it may concern:

Be it known that I, OLIVER McCARTHY, of Meriden, in the county of New Haven and State of Connecticut, have invented a new 5 Design for Coffin-Handles; and I do hereby declare the following, when taken in connection with accompanying drawing, to be a full, clear, and exact description of the same, and which said drawing constitutes part of this 10 specification, and represents a front view of an end portion of a handle-bar, showing one tip.

This invention relates to a design for the tip of the bar of coffin-handles; and it consists 15 in the configuration and ornamentation as shown in the accompanying illustration.

The tip is of circular shape in transverse section and is represented as springing from the end of the bar, and represents a band at 20 the base with a head gradually expanding in

an outwardly-curved line and represented as rounded at the end, and about midway the length of the expanding portion is the representation of an annular beaded band, the surface between the base and the band and between the band and the rounded end ornamented by the representation of floriated scrollwork, as shown in the accompanying illustration.

I claim—

The design for a coffin-handle, as described, and shown in the accompanying illustration.

In testimony whereof I have signed this specification in the presence of two subscribing witnesses.

OLIVER McCARTHY.
